UNITED STATES PATENT OFFICE.

JOHN M. DAVIDSON, OF PITTSBURGH, PENNSYLVANIA, ASSIGNOR TO WM. B. SCAIFE & SONS COMPANY, OF PITTSBURGH, PENNSYLVANIA, A CORPORATION OF NEW JERSEY.

CLEANING APPARATUS FOR SWIMMING-POOLS AND THE LIKE.

1,056,779.

Specification of Letters Patent. Patented Mar. 25, 1913.

Application filed November 29, 1912. Serial No. 733,970.

To all whom it may concern:

Be it known that I, JOHN M. DAVIDSON, a citizen of the United States, residing at Pittsburgh, Pennsylvania, have invented certain new and useful Cleaning Apparatus for Swimming-Pools and the Like, of which the following is a specification.

My invention relates to the art of dredging and is particularly designed to accomplish the cleaning of the bottoms of swimming tanks, and the like, where sediment collects, and it is desirable to remove this without emptying the water in the tank.

I have shown a form of apparatus embodying my invention in the accompanying drawing, wherein—

Figure 1 illustrates a broken section of a swimming tank with my cleaning device therein, and Fig. 2 is an under plan view of 20 the cleaner nozzle.

It is well known that in tanks, such as swimming pools for example, there is a rapid collection of sediment or slime on the bottom, due in part to the matter washed from the bodies of the bathers, and in part to chemicals used in purifying the water. Heretofore it has been considered necessary in order to clean such tanks to entirely empty the water therein. This is an expensive proceeding, because of the waste of water, the suspension of the use of the tank, and the cost of heating a new charge of water. I have discovered that the slime may be removed from the bottom of such a tank without removing the water, and without stirring up the sediment to contaminate the water.

It being understood that the bottom surface of a swimming pool is usually smooth and hard, as tiling, etc., and that the slime thereon is of an oily nature and contains hair and such matter, it will be understood that if the slime can be scraped off the bottom and then immediately removed without stirring, my objects can be attained. As shown in the accompanying drawings, I provide a rigid pipe B long enough to reach the bottom of the tank A and carrying on the lower end a sucker head C, made something after the fashion of a pneumatic carpet sweeper head, but covered on the under side with a scraper D which is made of soft

rubber and in ribbed form, as shown at d', and which by means of slots and bolts d can be adjusted to proper relation to outlet c. 51 This ribbed rubber part is designed to make the nozzle closely fit the bottom of the tank, to prevent the entry of water from the rear as the sucker head is moved over the surface, and also to push forward and pile up 61 the slime in front of the opening c. A guard E extends upward several inches at an angle of about 45° and is designed to prevent the escape of such part of the sediment as may be stirred up a little in advance of the opening c. The handle B is attached to a flexible pipe G and any convenient form of pump H, and it will be understood that in operation the pump withdraws from the tank only so much water as is necessary to wash in the slime accumulated in front of the sucker head as it proceeds over the bottom. The check valve F allows the nozzle to be lifted out of the water without escape of the sediment already collected. By this means I am able to entirely remove the slime without stirring or contaminating the water above, or removing any large portion of the water, or even interfering with the other use of 7 the tank. Other advantages will readily occur to those familiar with the art.

Having thus described my invention and illustrated its use, what I claim is:

1. In cleaning apparatus, a combined 8 scraper and sucker head comprising a casing with an open nozzle, a rubber scraper slidably mounted on the rear and bottom of the casing, an upwardly projecting shield on the front and top of the casing, and a check 9 valve in the casing, substantially as and for the purposes described.

2. In cleaning apparatus for tanks, a combined scraper and sucker head comprising a casing with an open nozzle, a resilient 9 scraper mounted on the rear and bottom of the casing, an upwardly forward projecting shield on the front of the casing, as and for the purposes described.

JOHN M. DAVIDSON.
